UNITED STATES PATENT OFFICE.

FRED O. WILLIAMS, OF BROOKLINE, MASSACHUSETTS, ASSIGNOR TO UNITED DRUG COMPANY, OF BOSTON, MASSACHUSETTS, A CORPORATION OF NEW JERSEY.

DESIGN FOR A HOT-WATER BOTTLE.

45,212.

Specification for Design.

Patented Feb. 3, 1914.

Application filed August 20, 1913. Serial No. 785,796. Term of patent 7 years.

To all whom it may concern:

Be it known that I, FRED O. WILLIAMS, a citizen of the United States, residing at 9 Strathmore road, Brookline, in the county of Norfolk and Commonwealth of Massachusetts, have invented a new, original, and ornamental Design for Hot-Water Bottles, of which the following is a specification, reference being had to the accompanying drawing, forming part thereof.

The figure is a plan view of a hot water bottle, showing my new design.

I claim:

The ornamental design for a hot water bottle, as shown.

Dated July 11, 1913.

FRED O. WILLIAMS. [L. S.]
